UNITED STATES PATENT OFFICE.

FRANK A. BULLINGTON, OF KANSAS CITY, MISSOURI, ASSIGNOR TO BULLINGTON MOTORS, OF KANSAS CITY, MISSOURI, A COMMON-LAW TRUST CONSISTING OF SOLOMON STODDARD, ERNEST E. HOWARD, AND FRANK BULLINGTON.

DIVIDED-CHARGE ROTARY ENGINE.

Application filed June 2, 1923. Serial No. 643,096.

To all whom it may concern:

Be it known that I, FRANK A. BULLINGTON, a citizen of the United States, residing at Kansas City, in the county of Jackson and State of Missouri, have invented certain new and useful Improvements in Divided-Charge Rotary Engines; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to rotary engines of the alternating piston type and particularly to that class of engines in which co-operating pistons move about the axis of an annular cylinder or working chamber at varying speeds to transmit power to a power shaft at a constant speed. Such engines are generically old and as a type they are well known.

The present invention comprehends means for greatly improving the operating efficiency of the engine for power purposes. The main difference between the present invention and prior engines or motors of the same general type is that the present invention provides means for dividing the charge so that there is more than one distinct explosion between co-operating pistons. In the present instance I have shown the invention designed so that two explosions take place for each power stroke of co-operating pistons and for the sake of clearness I have designated the first explosion as the primary explosion, the second explosion as the secondary explosion and their chambers as the primary chamber and the secondary chamber respectively, not on account of their relative importance as power generating factors but on account of the numerical order in which they occur.

As shown, the pistons alternately become the accelerated and retarded pistons in substantially the same manner that pistons of prior engines operate, with this essential difference: between co-operating pistons I arrange a floating, independently movable charge dividing partition, which separates the normal charge between two co-operat-

ing pistons into two parts, the first charge being ignited by a spark in the usual way and the second charge being exploded by spontaneous combustion due to the high compression under which it is placed by the movable partition moved by the explosion in the first chamber. The compression in the secondary chamber being relatively higher than that in the first chamber will cause the efficiency to rise in the secondary chamber due to the fact that the higher the compression, the greater the efficiency.

The novel construction of the invention will be apparent by reference to the following description in connection with the accompanying drawings, in which

Fig. 1 is a side view of the motor with one cover plate or side wall removed.

Fig. 2 is a detail perspective view of the charge dividing and controlling device.

Fig. 3 is a vertical, longitudinal, sectional view through an engine constructed in accordance with my invention, and

Fig. 4 is a sectional view on the line 4-4 of Fig. 3.

Referring now to the drawings by numbers of reference:

1 and 2 designate the two covers of complementary sections of the power generating part of the motor. The members 1 and 2 are provided with hub portions 3 and 4 which carry webs 5 and 6 spaced apart to provide a rotor chamber 7. At the periphery of the webs 5 and 6 are the two halves 8 and 9 of an annular cylinder or working chamber 10. The members 1 and 2 may be secured together by fastening devices, such as bolts 11, and the cylinder may be provided with the spark plug 12. The cylinder is connected with the rotor chamber 7 by an annular passageway 13 so that parts of the rotors 14 and 15 may extend into the cylinder to carry the pistons in a manner well understood.

In the present embodiment of the invention, the rotor 14 is carried by a shaft 16, one end of which is mounted in the hub 3 and the other being mounted in a recess 17 in the crank shaft carrier 18 on the end of the power delivery shaft 19 mounted in the hub 20 of the crank case 21, the crank case 21 being fastened to the wall 22 integral with the hub 4.

Concentric with the shaft 16 is a hol-

low shaft 23 which carries the rotor 15 and sleeved upon the shaft 16 is a third shaft 24 which is between the shaft 16 and the shaft 23, as clearly shown in Fig. 3 so that there are three concentric shafts, the inner and outer shafts being the rotor shafts and shaft 24 being the charge divider operating shaft.

The shaft 24 carries a rotor 25 (see Fig. 10 2) which is shown as co-extensive with the rotors 14 and 15 and located between them.

On the periphery of the rotor 25 is a plurality of charge dividing partition walls 26 of such shape as to be co-extensive with 15 the cross section of the cylinder 10.

The particular mechanism for alternating the pistons 27, 28, 29, and 30 (it being understood that pistons 27 and 29 are on one rotor and pistons 28 and 30 on the other) 20 will now be generically described, it being understood that for the present invention I make no special claim to the linkage for connecting the piston shafts to the power shaft 19 but in order to present a comprehensive disclosure of the operating conditions of the motor, I will briefly describe the linkage connections.

Two oppositely located single pin crank shafts 31 and 32 are mounted in the crank 30 carrier members 18 and 33, the crank carrier member 33 being rotatably mounted on the hub 4 and the member 18, as previously, explained, being carried by the shaft 19. The cranks 31 and 32 have on the ends nearest the cylinder, gears 34 and 35 which mesh with a fixed gear 36 keyed or otherwise secured to the hub extension 4. The opposite ends of the crank shafts 31 and 32 carry fly wheels 37 and 37' and the crank pins 38 40 and 39 are connected to the pins 40 and 41 of the crank arms 42 and 43 by connecting rods 44 and 45, the linkage mechanism being so arranged that it planetates about the gear 36 and effects the proper co-operative 45 relationship between the alternating pistons and delivers power to the power shaft 19 in a manner specifically referred to in one of my former applications but which need not be described here because the operation in 50 a general way of such an engine is well understood.

As heretofore mentioned, the prime feature of this invention is to provide a divided charge and control the charge in such 55 a way as to increase the efficiency of the engine. By reference to Figs. 2, 3 and 4 it will be observed that the shaft 24 carries two diametrically opposite arms 46 and 47 which are connected to the shaft 24 by the integral ring 48 and the keys 49 and 50. The diametrically opposite arms are interposed between springs 51 and 52 for the arm 46 and 53 and 54 for the arm 47. The inner 60 ends of the springs 51 and 52 bear against the arm 46 and the outer ends against the

walls 55 and 56 of a yoke 57 carried by the member 18. The springs 53 and 54 similarly bear against the arm 47 and against the walls 58 and 59 of a yoke 60, also carried by the member 18 diametrically opposite the yoke 57.

It will be observed that the partitions 26 are arranged about the rotor 25 at angles of 90 degrees and since the linkage mechanism between the alternating pistons and the 75 crank shaft carrier causes the crank shaft carrier to be driven at a constant uniform speed, it will be apparent that the variable movements of the power pistons will not effect the relative positions of the partition walls but that the pistons will have movement relative to the partition walls rather than the partition walls having movement relative to the pistons. Therefore, by reference to Fig. 1 it will be apparent that the piston 27 and one partition wall 26 have passed the intake port 61 to take in half of the charge of fuel and that the partition wall 26 and piston 30 have about completed taking in the second half of the charge. 90 When the piston 30 has closed off the port 61, the full charge will be confined between pistons 27 and 30 but it will be divided by the partition 26 between them.

When the crank shaft carrier has moved through an arc of 90 degrees, the piston 30 will be in the position occupied by piston 27 in Fig. 1 and piston 27 will be in the position occupied by piston 28 in Fig. 1 with the charge dividing partition 26 in the position occupied by the partition 26'. The divided charge in the primary chamber 62 and the secondary chamber 63 will have the usual compression, for example, about five atmospheres.

If the timing mechanism of the engine is properly designed, the spark plug 12 will cause an explosion or ignition in the primary chamber 62, it being understood that pistons 30 and 27 at this time will be on dead center 110 position. The exploded charge, of course, will exert pressure equally in all directions, tending to drive the piston 27 forward, that is, in a clockwise direction, but since the partition 26' is a floating partition, capable 115 of independent movement and is yieldingly positioned by the springs 51, 52, 53, and 54, it is obvious that the expansive force of the ignited charge in the primary chamber 62 will move the partition 26' in a contra-clockwise direction, constricting the secondary chamber 63 and thereby building up the compression pressure in the chamber 63 high enough to cause the part of the charge in the secondary chamber 63 to explode by 120 spontaneous combustion, due to the high compression in that chamber and since the higher the compression the greater the efficiency derived from the exploded charge, 125 it will be apparent that greater power will 126

be derived from the exploded charge by the two explosions (one at a higher pressure than the other) between the pistons than could be derived if the charge were exploded at a lower pressure.

The high pressure desired in order to get the highest efficiency could not be provided between two complementary power pistons with any degree of success because if the 10 pressure in the primary chamber approached the critical pressure, there would be liability of a premature explosion such as often happens in every day practice where the compression is too high. Therefore, in order to provide a practical embodiment of a known principle, to wit: that the higher the compression, the higher the efficiency from the exploded charge, I have devised an invention which insures uniform operation 20 without attendant disadvantages.

As the pistons 27 and 30 move clockwise after the explosions above referred to they will assume the positions occupied by pistons 28 and 29 in Fig. 1; first the primary chamber 62 and then the secondary chamber 25 63 exhausting through exhaust port 64. When they have assumed these positions, the pistons 30 and 29 will have occupied the positions now occupied by pistons 28 and 27. 30 This principle of alternating pistons, however, is so well known that it is not deemed necessary to specifically describe it here. Suffice it to say that between each set of alternating pistons there is a charge-dividing 35 partition 26 whereby the charge is divided into two parts, the charge in the primary chamber being ignited at relatively low pressure and the charge in the secondary chamber being ignited at relatively high 40 pressure, the exploded charges in the two chambers combining to produce power delivered to two co-operating, alternating pistons and by this arrangement I have materially increased the efficiency of the engine 45 over that type in which a single charge at relatively low pressure is ignited by a spark plug in a single chamber between two co-operating pistons.

According to my invention, the explosion pressures in chambers 62 and 63 co-operate to deliver the power to the pistons; for example, when the charge is exploded in chamber 62, it will move the partition 26' toward piston 27 approximately to the dotted line 55 position 65. Therefore, the secondary chamber 63 will be constricted and the contents thereof will be compressed high enough to cause spontaneous combustion. The pressure at which the fuel in chamber 63 will 60 at this time be exploded will be higher than the compression pressure in chamber 62 at the time of its explosion. Consequently the explosion pressure in chamber 63 will be higher than the explosion pressure which 65 previously occurred in chamber 62. There-

fore, the partition 26' will, under the force of the exploded charge in chamber 63, move back to approximately the position occupied by partition 26" or to such position that the mean of the pressures in the two chambers will be higher than the explosion pressure in chamber 62. In other words, the mean of the explosion pressure in the two explosion chambers, resulting in action on the two pistons, will be somewhat less than the 75 initial explosion pressure in the secondary chamber, but it will be higher than the initial explosion pressure in the primary chamber. Therefore, I obtain the highest efficiency from the fuel charge. 80

When the engine is operating, it is conceivable that the explosion may take place in both the primary chamber and the secondary chamber by spontaneous combustion; for example, if the engine is operating, the 85 explosion pressure in the secondary chamber 63 will not be expended at the time that the pressure in the primary chamber is exhausting, for if piston 29 has moved to position to exhaust, the exploded gases from the chambers between the piston 29 and the partition 26", between 28 and 29, the expanding gases in the chamber between 26" and the piston 28 will move partition 26" slightly away from the piston 28, due to the 95 fact that there is now no counter-acting pressure in the space between 29 and 26". This motion will be communicated to the entire rotor 25, causing partition 26' to constrict the primary chamber and tending to 100 raise the compression pressure in primary chamber high enough to cause spontaneous combustion. Then the engine will operate without the spark, and it is obvious that this action will take place under proper 105 conditions.

What I claim and desire to secure by Letters-Patent is:

1. In a rotary alternating piston engine, a cylindrical casing, pairs of pistons therein rotating about a common axis, the pistons having relative movements to compress fuel charges to combustible pressures, and charge-dividing partitions between complementary pistons separating the combustion spaces between the complementary pistons into a primary explosion chamber and a secondary explosion chamber so that the two separated parts of each fuel mixture charge confined between two complementary power pistons will be independently exploded one after the other, the charge in the primary chamber being exploded at lower pressure than that in the secondary chamber. 115

2. In a rotary alternating piston engine, a cylindrical casing, pairs of pistons therein rotating about a common axis, the pistons having relative movements to compress fuel charges to combustible pressures, and floating charge-dividing partitions separating 120

125

130

the combustion spaces between complementary pistons into a primary explosion chamber and a secondary explosion chamber so that the two separated parts of each fuel mixture charge confined between two complementary power pistons will be independently exploded one after the other.

3. In a rotary alternating piston engine, a cylindrical casing, pairs of pistons therein

10 rotating about a common axis, the pistons having relative movements to compress fuel charges to combustible pressures, and independently movable charge dividing partitions between complementary pistons

15 separating the combustion spaces between the complementary pistons into independent explosion compartments so that the two separated parts of each fuel mixture charge confined between two complementary power pistons will be independently exploded one after the other.

4. In a rotary alternating piston engine, a cylindrical casing, pairs of pistons therein

20 rotating about a common axis, the pistons having relative movements to compress fuel charges to combustible pressures, and yieldingly-held charge-dividing partitions between complementary pistons to divide the combustion spaces between them so that the two separated parts of each fuel mixture charge confined between two complementary power pistons will be independently exploded one after the other.

30 5. In a rotary alternating piston engine, a cylindrical casing, pairs of pistons therein

35 rotating about a common axis, the pistons having relative movements to compress fuel charges to combustible pressures, charge- dividing partitions between the pistons

40 dividing each charge into two separate parts so that the two separated parts of each fuel mixture charge confined between two complementary power pistons will be independently exploded one after the other,

45 and means for imparting a uniform movement to the partitions.

6. In a rotary alternating piston engine, a cylindrical casing, pairs of pistons therein

50 rotating about a common axis, the pistons having relative movements to compress fuel charges to combustible pressures, charge-

dividing partitions between the pistons dividing each charge into two separate parts so that the two separated parts of each fuel mixture charge confined between two complementary power pistons will be independently exploded one after the other, and yielding means movable in response to the movement of the pistons for driving the partitions at a constant speed.

7. In a rotary alternating piston engine, a cylindrical casing, pairs of pistons therein

25 rotating about a common axis, the pistons having relative movements to compress fuel charges to combustible pressures, a constant speed power shaft driven by the pistons, and charge-dividing partitions between the pistons driven at the speed of the power shaft, the charge dividing partitions separating each fuel charge into two separate parts so that the two separated parts of each fuel mixture charge confined between two complementary power pistons will be independently exploded one after the other.

8. In a rotary alternating piston engine, a cylindrical casing, pairs of pistons therein

30 rotating about a common axis, the pistons having relative movements to compress fuel charges to combustible pressures, a constant speed power shaft driven by the pistons, and charge-dividing partitions between the pistons yieldingly driven at the speed of the power shaft, the charge dividing partitions separating each fuel charge into two separate parts so that the separated parts of each fuel mixture charge confined between two complementary power pistons will be independently exploded one after the other.

9. In an internal combustion engine having a cylindrical wall, a piston within the wall, means associated with the wall and the piston to provide a combustion chamber, and a floating partition in the combustion chamber dividing it into two compartments,

35 means for feeding a fuel charge mixture into the two compartments before explosion so that the two separated parts of each fuel mixture charge will be independently exploded one after the other.

In testimony whereof I affix my signature.

FRANK A. BULLINGTON.
